UNITED STATES PATENT OFFICE.

ORLANDO B. SHEDD, OF ST. JOHNSVILLE, NEW YORK.

BOW-FACING OAR.

SPECIFICATION forming part of Letters Patent No. 691,080, dated January 14, 1902.

Application filed May 3, 1901. Serial No. 58,618. (No model.)

To all whom it may concern:

Be it known that I, ORLANDO B. SHEDD, a citizen of the United States, residing at St. Johnsville, in the county of Montgomery and 5 State of New York, have invented new and useful Improvements in Oars, of which the following is a specification.

This invention relates to oars of the bow-facing type, it having two connected sections, 10 one a handle and the other a blade, which latter is adapted to be dipped into the water to propel a boat forward while the operator manipulating the handle portion faces the bow of such boat, and the improved oar is 15 thoroughly simple and light yet perfectly strong.

The invention includes as one of its features an oar in two sections having rounded ends and U-shaped plates fastened to said 20 ends, the channels of the plates being adapted to receive chains—say of the well-known sprocket type—connected at their ends to the respective sections of the oar, and said sections are adapted to receive pivots extending 25 from a connecting member, hereinafter described, whereby through said chains when the handle portion of the oar is actuated the blade thereof will be oppositely oscillated. The channel-plates serve to maintain the 30 sprocket-chains in their operative positions and against side play, so that there will result no lost motion in the operation of the oar. The said sections receive sleeves through 35 which pivot-pins are adapted to extend, said pins being rigid upon a connecting member and being connected by a tie-bar, this construction being a decidedly stable and efficient one.

I desire at this point to state that I employ 40 the term "chain" as a generic one, for equivalent means may be employed for the same purpose, though a chain is preferable.

The invention is clearly illustrated in the accompanying drawings, which, with the characters of reference marked thereon, form a 45 part of this specification, and in which—

Figure 1 is a view in perspective of the oar mounted in place in the position it occupies in rowing a boat. Fig. 2 is a detail in elevation of one of the sections of the oar. Fig. 3 is a sectional side elevation of a connecting device for the sections of the oar. Fig. 4 is a

similar view of an oar-support. Fig. 5 is an elevation of a channel-plate.

Like characters refer to like parts in all the 55 figures of the drawings.

The oar is denoted in a general way by A, and it is divided into two operatively-connected parts, as 2 and 3, the former constituting the blade-section and the other the 60 handle-section, and being constructed, preferably, though not necessarily, of wood. The adjacent ends of the sections are rounded, and they are adapted to receive channeled or grooved plates, as C, of metal, substantially U shape, fastened to the sections by screws or similar means. Each section carries two parallel plates, and they are adapted to receive bands, as 4, as the sections oscillate. Said bands consist, preferably, of sprocket- 70 chains, which are connected at their ends to said sections and which serve to transfer the power of the handle-section 3 to the blade-section 2 for the purpose of operating the latter, and these plates hold the chains positively in position and prevent any sagging thereof. The chains are fixedly connected at one end to one section of the oar—say the blade part thereof—while the opposite ends thereof are adjustably joined to the handle- 75 section for the purpose of tensioning said chains. Each chain of course is guided by a channeled plate on one section and the adjacent plate on the other section, and the plates on the handle-section receive in their 80 channels projections, as 5, perforated to receive the threaded shanks 6, having hooks to enter the links at what might be termed the "inner" ends of the chains. Said threaded shanks receive nuts, as 7, engaging the fixed 85 projections. By turning the nuts the chains may be either tightened or loosened. The sections are united by a connecting member, (designated in a general way by B,) including a longitudinal body, as 8, adapted to fit 90 against and overlap the under faces of the sections 2 and 3. This body has at or near its ends the rigid pivot-pins 9, extending perpendicularly therefrom and which may be cheaply cast in one piece with the longitudinal body 8. These pivot-pins are adapted to project through and beyond fixed bearing-sleeves, as 10, driven through the sections of 95 the oar, it being evident from this that the 100

said sections are oppositely vibratory. The pins are threaded at their upper ends to receive the holding-nuts 12, which are adapted to engage the tie-rod 13, uniting the said pins and strengthening them to better resist the lateral stress to which they are subjected.

The body 8 has on its under side a depending lug 14, perforated to receive the pivot pin or bolt 15, connected to the upper ends 10 of the parallel lugs 16, rising from the base-plate 17, which is fastened in some suitable manner to the gunwale of a boat. The base-plate, with its lugs and pivot, constitutes a simple oar-support and permits the dipping 15 of the oar-blade into and its removal from the water while propelling said boat.

The invention is not limited to the precise construction previously described, for variations within the scope of the appended claims 20 may be made.

Having described the invention, I claim—

1. An oar in two sections having rounded ends and substantially **U**-shaped, channel-plates connected to said ends and chains lying in the channels of the plates and connect- 25 ed respectively with said sections.
2. An oar in two sections having rounded

ends, substantially **U**-shaped, channel-plates connected to said ends, chains lying in the channels of the plates, and means for ad- 30 justably connecting the chains with said sections.

3. An oar in two sections having rounded ends, substantially **U**-shaped, channel-plates connected to said ends, chains lying in the 35 channels of the plates, hooks on the sections for engaging one end of each chain, the hooks having threaded shanks, projections on said sections to receive said shanks, and nuts on the latter.

4. An oar in two sections, sleeves extending through the sections, a member having bolts extending through the sleeves, chains connecting said sections, a tie-bar uniting the 40 bolts, nuts on said bolts, and channeled plates, the channels of which receive said chains.

In testimony whereof I have hereunto set my hand in presence of two subscribing witnesses.

ORLANDO B. SHEDD.
